C. A. McNEAL,
HEADLIGHT REFLECTOR,
APPLICATION FILED JAN. 15, 1920.

1,394,319.

Patented Oct. 18, 1921.

UNITED STATES PATENT OFFICE.

CHARLES A. MCNEAL, OF COLUMBUS, OHIO, ASSIGNOR OF ONE-HALF TO FRED EARL FULLER, OF COLUMBUS, OHIO.

HEADLIGHT-REFLECTOR.

1,394,319.

Specification of Letters Patent.

Patented Oct. 18, 1921.

Application filed January 15, 1920. Serial No. 351,551.

To all whom it may concern:

Be it known that I, CHARLES A. MCNEAL, a citizen of the United States, resident of Columbus, in the county of Franklin and

5 State of Ohio, have made a certain new and useful Invention in Headlight-Reflectors; and I declare the following to be a full, clear, and exact description of the same, such as will enable others skilled in the art
10 to which it appertains to make and use the invention, reference being had to the accompanying drawings, and to letters or figures of reference marked thereon, which form a part of this specification.

15 Figure 1 is a central cross section of the invention.

Fig. 2 is a face view of the same.

Fig. 3 shows a detail edge view and a detail perspective view of one of the reflector
20 sections.

The invention has relation to headlight reflectors, for automobiles, or for use wherever a headlight would be needed, and has for its object to provide an improved reflector wherein glare will be eliminated and the field or cone of reflected light will be made up of elements or rays equally distributed or appearing as equalized throughout the same, or whereby the field of reflected light thrown upon the roadway will appear equally illuminated throughout.

The invention consists in the novel construction and combinations of parts, as hereinafter set forth.

35 In the accompanying drawings illustrating an embodiment of the invention, the numeral 2 designates the reflector of concavo-convex form, and whereon are set, fixed or molded, or wherein are stamped a plurality
40 of or multiplicity of plane-surface reflector sections 3, 3, covering the entire surface of the reflector and forming the reflecting surface thereof by suitable adaptation. These reflector sections are respectively of comparatively small size and are arranged in
45 annular series. The sections as shown are polygonal in form and interfitting.

The sections 3, 3, are arranged respectively or individually at the proper angle
50 to reflect the rays of light from a light source or bulb 4, located at the focal point

approximately of the reflector, to form a field of reflected light or a cone of light, the upper limit of which will lie below the eyes of an approaching driver and the lower 55 limit of which will lie upon the roadway sufficiently close to the headlight to properly illuminate the road, this being accomplished by giving each individual reflector section 3 an inclination with respect to the axis of 60 the reflector which will differ from that of the remainder of the reflector sections or any one of said remainder. Thus the angle of incidence of a ray of light made with each unit will be different from that made 65 with any other one in a section taken in a plane perpendicular with the axis of the reflector.

The reflector sections 3, being arranged as stated, will diffuse the rays of light reflected therefrom, whereby the field or cone of reflected light will have the elements or rays thereof appearing as equally distributed or substantially equalized throughout the same, thereby avoiding the formation of 70 a central bright spot of reflected light and alternate light and dark rings surrounding said spot, upon the roadway, and which are unavoidable in the concave or parabolic reflector as adapted for use as a headlight. In 75 practice the concave or parabolic reflector so adapted for headlight use, throws out a cone of reflected light, which is so positioned as to throw a glare into the eyes of an approaching driver, and into the eyes of 80 a driver of a passing car going in the opposite direction, and applicant by the use of the reflector sections arranged as stated, avoids this glare. Owing to the comparatively small area of each reflector section, 85 the diffusion of the reflected light rays incident thereto, will be limited, but will be sufficient to break up the aforesaid central bright spot and the light and dark rings surrounding said spot, and equalize the 90 illumination.

I claim:

A headlight reflector of concave form, made up of a multiplicity of plane units 100 angularly related to each other, said units being individually of comparatively small size and each having an inclination with

respect to the axis of the reflector differing from that of any other unit, said units disposed in the reflector so as to reflect the rays of light from a common source located at 5 the focus of the reflector downwardly and forwardly in a substantially definite cone of equally distributed light rays.

In testimony whereof I affix my signature in presence of two witnesses.

CHARLES A. McNEAL.

Witnesses:

J. L. BACHMAN,
LEE F. JOHNSTON.
